UNITED STATES PATENT OFFICE.

GEORGE HILLARD BENJAMIN, OF NEW YORK, N. Y.

EVAPORATOR AND METHOD OF OPERATING SUCH EVAPORATOR.

1,355,935.

Specification of Letters Patent. Patented Oct. 19, 1920.

Application filed February 23, 1918. Serial No. 218,618.

To all whom it may concern:

Be it known that I, GEORGE HILLARD BENJAMIN, a citizen of the United States, residing at New York, in the county and State of New York, have invented certain new and useful Improvements in Evaporators and Method of Operating Such Evaporators, of which the following is a specification.

In U. S. Letters Patent No. 1,225,118 granted to F. T. Evans on May 8, 1917, there is described a method of obtaining pure water from salt water, which consists in evaporating salt water by heat to obtain a watery vapor containing a small percentage of salt, then superheating the vapor so derived under conditions where no water is present as a body, and finally condensing the superheated vapor. In such patent there is described an apparatus for carrying the above described method into effect. This apparatus, in practice, was found to be successful, but is open to the objection that high temperature steam is required to superheat the vapor, which high temperature steam is not always available on all vessels where evaporating apparatus may be employed.

My invention relates to apparatus and method of operating said apparatus, by reason of which the above described method may be carried into effect, but which differs from that described in the patent of Evans in that the superheating of the vapor is accomplished by means of the temperature effects of an electric current transmitted through suitable apparatus. By reason of my improved apparatus, I am able to effect the original evaporation of the salt water to form the vapor, by means either of steam of low temperature, or the temperature effects of an electric current, and the superheating of the vapor by the temperature effects of an electric current, with the heating mediums susceptible of independent control. Further, through the use of the temperature effects of an electric current for superheating the vapor, I am able to obtain higher temperature effects than is the case with superheated steam, and much more readily controllable, and hence much more economical in application.

The accompanying drawings will serve to illustrate my invention, in which:

Figure 1 is a vertical section through a form of my apparatus, where the evaporating and superheating chambers are each ar-

ranged to be heated by the temperature effects of electric current.

Fig. 2 is an elevation of the superheating chamber, looking to the right of the upper portion of Fig. 1, with the bottom broken away to show the superheating elements.

Fig. 3 is a horizontal section taken on the line III—III of Fig. 1.

Fig. 4 is a horizontal section taken on the line IV—IV of the evaporating chamber shown in Fig. 1.

Fig. 5 is a vertical section corresponding to Fig. 1, showing an elevation of a modified form of my evaporating apparatus, with the superheating chamber in this figure shown to be heated by the temperature effects of electric current, and the evaporating chamber by steam; also showing the heating elements through which the electric current is utilized in the superheating chamber, swung out of the superheating chamber for cleaning.

Fig. 6 is an enlarged vertical section of one of the electrical heating elements, shown in the superheating chambers of Figs. 1, 5 and 10.

Fig. 7 is a horizontal section taken on the line VII—VII of Fig. 6.

Fig. 8 is an enlarged horizontal section taken through one of the electrical heating elements of the evaporating chamber shown at the bottom of Fig. 1.

Fig. 9 is a side elevation illustrating the means employed to support the door and heating elements of the evaporating chamber when in and when removed from the evaporating chamber.

Fig. 10 is a vertical section of another form of my evaporator, showing the heating elements in the evaporating chamber formed of steam coils as shown in Fig. 5, and a separate electrical heating element situated below the steam coils, and further showing the superheating chamber mounted over the evaporating chamber.

Fig. 11 is a horizontal section on the line XI—XI of Fig. 10, and

Fig. 12 is a horizontal section on the line XII—XII of Fig. 10.

In the various views, similar numerals indicate like parts.

In the drawings, 15 indicates the evaporating chamber, which is of the usual construction, and provided with a removable door 16 mounted upon the wheeled support 110

17. Situated within the chamber 15, are the heating elements 18—19—20. In Fig. 1 the electrical heating element 18 occupies the whole of the water space 21. In Fig. 5, the steam heating element 20 occupies the whole of the water space 21, and in Fig. 10 the electrical heating element 19 occupies the lower portion of the water space 21, and the steam heating element 20 the upper portion 10 of the water space 21.

I wish to have it understood that I do not limit myself in any wise to the amount of space which the heating elements shall occupy within the evaporating chamber 15, or 15 the proportions of the space which shall be occupied respectively by the electric and steam heating elements, nor do I wish to limit myself in any wise to the particular construction of the heating elements, as they 20 may be considerably modified from those shown.

In Fig. 1 the heating element 18 consists of four symmetrically disposed shaped metal tubes 22, mounted upon and supported by a casing 23 connected at one end to the door 16. Situated within each of the tubes 22, is a porcelain plate 24, having helical grooves 25 formed in its surface, in which is wound a spiral coil 26. The plate 30 24 is detachably connected to the casing 23 by nuts 27. The coils 26 are connected in multiple to conductors 28—29 respectively connected to minus and plus spring contact plates 30—31 on the front of the door 16. 35 Arranged to coöperate with contact plates 30—31, is a switch 32, pivotally mounted on the front of the evaporator, as shown at 33. By means of this switch, the coils 26 can be thrown into circuit with a source of 40 electricity exterior to the evaporator. The electrical heating element shown in Figs. 10 and 12, consists of a metallic annulus 34, connected through tube 35 to the front of the evaporator shell. Located within the 45 annulus is a clay annulus 36, having a spiral groove 37 on which is helically wound a spiral coil 38. This coil is connected to the contact plates 30—31 in the same manner as is shown in Fig. 4. The metallic annulus 50 34 is supported above the bottom of the evaporator by posts 39, the object of which is to allow space for circulation of water around the annulus, and keep the bottom of the annulus out of contact with the salt which forms on the bottom of the evaporator.

In Figs. 5 and 10 the steam heating element consists of the horizontally disposed manifolds 40—41, respectively connected to 60 the door 16. Interposed between these manifolds are the helical coils 42. In Figs. 5 and 10 the steam heating element 20, considered as a whole, is attached to the door 16 and adapted to be drawn out of the 65 evaporator for cleaning, and the same is

true of the electrical heating element 18 in Fig. 1. In the construction shown in Fig. 10, the electrical heating element is not attached to the door, but permanently attached to the bottom of the evaporator. 70

In Fig. 10, a casing 43, open at the bottom, is arranged over the annulus 34, and situated above this casing is a pipe 44 which is carried through the manifolds 40—41. In Fig. 5 the helical coils 42 are arranged in line along the manifolds 40—41, the manifolds being straight. In Fig. 11, the manifolds are shown as formed as annuli, disposed horizontally with the helical coils arranged around the annuli. In Figs. 5 and 80 11, the manifolds 40—41 are shown as adapted to coact with steam connections 45—46 mounted on the door 16, which steam connections are adapted to coact with other steam connections 47 secured to the external 85 surface of the shell of the evaporator, and they in turn adapted to connect with steam pipe 48 leading to the source of steam supply, the object of which arrangement is to provide that the main steam connection to 90 the evaporator shall remain unbroken when the door 16 and the heating elements attached thereto, are removed from the evaporator shell for cleaning.

It will be understood that when the door 95 shown in Fig. 10 is removed from the evaporator, pipe 44 is carried out with the door, moving over the top of the casing 43.

Located in the top of the evaporator shell 15, are the usual baffles 49—50. Connected 100 to the top of the evaporator shell is a pipe 51, which leads into the bottom of the superheater shell 52. 53—54 represent pipes connecting the evaporator shell, by means of which salt water or fresh water for cleaning, may be introduced into the evaporator shell 15. In the construction shown in Figs. 1 and 5, the superheater 52 is located at a distance from the evaporator 15. In the construction shown in Fig. 10, the superheater 52 is located immediately above the evaporator 15. I do not limit myself in any wise to the position of the superheater 52 as regards the evaporator 15. In each of the figures, the superheater is shown as 115 located above the evaporator. This is not essential. It may be on a level with the evaporator or below it. The only requirement being that no water will pass from the evaporator 15 into the superheater 52. The 120 reason for this is that it is impossible to superheat vapor in the presence of water. Consequently, the arrangement of parts must be such that there is no water in the superheater at any time. In practice, it is 125 found that there will be no water, but should water condense, arrangements should be made to tap off the water so as not to leave any water which may be absorbed by the vapor as it is superheated. 130

The superheater 52 is provided with a door 55. The top of the door is connected through a link 56 to a pivoted arm 57 on the top of the superheater. By reason of this construction, the door and the heating elements which it supports, may be swung away from the superheater shell, as shown in Fig. 5, for cleaning or otherwise.

Extending inwardly, horizontally from the top of the door 55, is an annulus 58. A horizontal plate-like body 59 extends inward across the shell 52 in line with the bottom of the door. Depending from the annulus are a series of electrical heating elements 60. Each heating element consists of a cylindrical body of clay 61, on the surface of which is formed a spiral groove 62, in which is wound a wire helix 63. Surrounding the groove and helix is a metal tube 64, closed at the bottom, which depends from the annulus 58. The surface of this tube is shaped to correspond with the general contour of the cylindrical body 61. Supported in plate 59 is an upwardly extending tube 65. A space is left between the top of this tube and the bottom of the exterior of the annulus 58. A third tube 66 depends from the annulus 58, the bottom of this tube being flared outward, as shown at 67, Fig. 1. The three tubes 64-65-66, are arranged concentrically and have the same surface configuration. Situated over the cylindrical body 61, and secured by a screw thread in the annulus 58, are removable caps 68, which may be removed for examination of the connections to the helix 63. The helix 63 is connected in multiple to the conductors 69-70, which are in turn connected to switches 71 adapted to coöperate with contact plates 72-73 mounted on the exterior of the superheater, and connected to a suitable source of electricity. The plate 59 has formed in it, perforations 74, as shown in Fig. 1.

It will be observed, that by reason of the spacing of the tubes 64-65-66, channels exist between them, through which circulation of the vapor may take place, the circulation being upward between the tubes 64-65 and downward between the tubes 65-66. The advantage of this arrangement is that the vapor passes within the influence of the heat from the heating elements, twice as a film. This is indicated by the arrows in Fig. 6.

The operation of my improved device will be readily understood. Salt water is introduced into the evaporating chamber through pipe 53, until the water reaches the top of the heating elements, whatever the character of the elements employed, leaving a space between the top of the baffles 49-50. Evaporation is accomplished in Fig. 1 by the electric heat being trans-

mitted to the water, the result being the formation of a vapor which passes off through pipe 51 to superheater 52. In superheater 52 the vapor passes upward through the perforations 74 in the plate 59, and as a film through the channels between the tubes 64-65-66, passing first in an upward direction and then in a downward direction, and thence out of the superheater through the pipe 75.

In Fig. 5 evaporation is caused by the temperature of the steam passing through the heating coils; in Fig. 10 by the temperature of the steam passing through the heating coils, supplemented by the temperature due to the electrical heating element 19 in the bottom of the evaporator.

In the construction shown in Fig. 10, the disposition of the parts is for the purpose of obtaining a circulation of the water to be evaporated. The heat developed by the heating element 19 causes the water to move upward in the direction of the arrow through the pipe 44 and out of the pipe in a downward direction. This construction possesses an advantage over that shown in Figs. 1 and 5, and for the reason that the temperature may be increased through the electrical heating element 19, circulation effected and evaporation made more rapid than is the case where no arrangement is provided for effecting circulation of the water. The vapor, after passing through pipe 51 as above described, passes as a film over the electrical heating element in the superheater 52, and is therein effectually superheated, that is, heated to such an extent as to cause it to deposit practically all of the salt carried by the vapor. It will be understood from the description, as far as given, that the heating elements of the evaporator and superheater may be independently controlled, and thus the temperature exhibited in these two vessels determined at will. Thus, the temperature exhibited in the evaporator vessel may be such as to cause a slow or rapid evaporation of the water, and the temperature exhibited in the superheater vessel may be such as to superheat the vapor to any desired temperature. In certain conditions of use of evaporators, it has been found unnecessary to superheat the vapor delivered from the evaporator, for instance, when the vessel is at rest or moving on an even keel, but highly desirable to superheat the vapor when the vessel is pitching in a seaway, which tends to produce priming from the evaporator. A further effect is obtained by the use of the apparatus described, which is that if the vapor is superheated to a high degree, the temperature units bound with the vapor, are in a condition to be radiated with great rapidity.

Having thus disclosed my invention, I claim:

1. In an evaporator, the combination of an evaporating chamber, a steam heating apparatus located therein through which steam may be circulated and the temperature controlled, a superheating chamber, an electric heating apparatus located therein through which electric energy may be applied and the temperature controlled, together with means whereby the vapor set free in the evaporating chamber will be carried into the superheating chamber.

2. In an evaporator, the combination of an evaporating chamber, two sources of heat located within said chamber and independently controllable, a superheating chamber, a source of heat independently controllable located within said chamber, together with means whereby the vapor generated in the evaporating chamber will be carried into the superheating chamber to be superheated therein.

3. In an evaporator, the combination of an evaporating chamber, a steam heating apparatus located in said chamber, an electric heating apparatus located in said chamber, said heating apparatus separately controllable, a superheating chamber, an electric apparatus located in said superheating chamber and separately controllable from the heating apparatus of the evaporating chamber, together with means whereby the vapor set free in the evaporating chamber will be carried into the superheating chamber.

4. In an evaporating apparatus, the combination of an evaporating chamber, means for applying temperature to the interior of the chamber to effect evaporation of liquid in said chamber, a superheating chamber, means whereby the vapor set free in the evaporating chamber will be carried into the superheating chamber, means located in the superheating chamber whereby the vapor introduced into the chamber will be caused to pass as a film over the heating unit in such superheating chamber, a heating device in said superheating chamber, together with means for separately controlling the temperatures exhibited through the heating apparatus in the evaporating and superheating chambers.

5. In an evaporator, the combination of an evaporating chamber, a removable door, a heating unit mounted upon the door, a superheating chamber, a removable door, a heating unit mounted upon the door, a pipe connection between the top of the evaporating chamber and the bottom of the superheating chamber, together with means for separately controlling the temperature effects of the heating units of the evaporating and superheating chambers.

6. In an evaporator, the combination of an evaporating chamber adapted to contain a liquid, a heating unit adapted to be immersed in the liquid and through its temperature effects set free a vapor, a superheating chamber, means located in such chamber whereby the vapor introduced into said chamber will pass through such chamber as a film, means in said chamber for superheating such film during its passage, means interposed between the evaporating and superheating chambers for carrying the vapor set free in the evaporating chamber into the superheating chamber, together with means for separately controlling the application of heat through the instrumentalities described in the evaporating and in the superheating chambers.

7. In an evaporator, the combination of an evaporating chamber, means in said chamber for applying heat to vaporize the fluid contained in said chamber, a pipe leading from the top of said evaporating chamber through which the vapor set free in such chamber will be carried from the evaporator, together with means located external to said evaporating chamber for superheating the vapor as a film as it passes from said evaporator, and said evaporator and superheating means provided with independent heat controlling apparatus.

8. The method of converting salt water into fresh water, which consists in subjecting salt water to the action of heat in a closed vessel to set free a vapor, conveying the vapor to a closed vessel, transmitting the vapor through such closed vessel as a film and subjecting the film to the action of a controllable high temperature to superheat the film.

In testimony whereof I affix my signature. 105
GEORGE HILLARD BENJAMIN.
